UNITED STATES PATENT OFFICE.

JOHN H. DUNCAN AND FRANK A. HALE, OF SYRACUSE, NEW YORK.

CISTERN-CLEANER.

SPECIFICATION forming part of Letters Patent No. 410,159, dated September 3, 1889.

Application filed November 26, 1888. Serial No. 291,902. (No model.)

To all whom it may concern:

Be it known that we, JOHN H. DUNCAN and FRANK A. HALE, of Syracuse, in the county of Onondaga, in the State of New York, have 5 invented new and useful Improvements in Cistern-Cleaners, of which the following, taken in connection with the accompanying drawings, is a full, clear, and exact description.

- 10 Our invention relates to an improved device for cleaning cisterns, and has for its object the production of a simple and effective cleaner, which shall be lowered to the bottom of the cistern, and shall then be opened, allowing the air contained in the cleaner to escape upward and causing the pressure of the water to force open a valve in the base of the cleaner, causing the mud and other refuse in the bottom of the cistern to be forced into 20 said opening as the contained air is forced upward out of the cleaner, forming a vacuum; and to this end it consists, essentially, in a suitable receptacle of desirable size to be easily raised and lowered and provided near its upper portion with a valve suitably connected to the hand of the operator, whereby the same may be opened when desired, and a valve in the base of the said receptacle, into which the mud is forced when the upper valve is opened.
- 25 It furthermore consists in the detail construction and arrangement of the parts, all as hereinafter more fully described, and pointed out in the claims.

In specifying our invention reference is had 35 to the accompanying drawings, forming a part of this specification, in which like letters indicate corresponding parts in all the views.

Figure 1 is a side elevation of our improved cistern-cleaner, parts thereof being broken 40 away, respectively, at the top and bottom for the purpose of illustrating the construction and arrangement of the valves. Fig. 2 is a side elevation, partly in section, of a modified form of the upper valve of our improved cistern-cleaner; and Fig. 3 is an elevation of the device for opening and closing the valve illustrated in Fig. 2.

A represents any suitable receptacle of desirable form and construction, preferably 45 adapted to be easily lowered and raised in the operation of cleaning the cistern, provided at its base A' with a valve B and at its top, pref-

erably in the center thereof, with the upper valve.

For the purpose of readily manipulating 55 the receptacle A we provide any suitable handle, (not shown,) secured to a rod or standard D, which is mounted and supported by a collar E, secured to the receptacle A by suitable braces F, attached thereto in any desirable manner. The standard D is provided with a flange or shoulder D', adapted to abut against the collar or hub E when the cleaner is being inserted into the cistern and forces the same downward, and the lower extremity 60 D² of the standard D is provided with an annular shoulder D³, mounted in a suitable encircling-hub G, secured in any desirable manner upon the top of the cleaner, preferably in the center thereof, and provided at its top 65 with an annular flange or ring G', forming a stop to the upward movement of the shoulder G³. As the cleaner is being forced into the cistern this shoulder D³ abuts against an aperture a, provided in the top a' of the receptacle A, and is securely closed, preventing the escape of the air contained in the receptacle A.

In the base A' of the cleaner we provide any 70 suitable valve B, which is opened inwardly, and when the cleaner has been forced through the water to the bottom of the cistern the standard D is slightly raised, by means of the handle secured thereto, until the shoulder D³ abuts against the flange or ring G' of the collar G, uncovering the aperture a, whereupon 75 the pressure of the water forces the valve B inward and drives out the air through said aperture a into the hub G in the space G², interposed between the top a' and the shoulder 80 D³ of the standard, whence it is forced outward into the water through apertures b, leading therefrom, and then escapes through the water, producing a vacuum in the cistern-cleaner and allowing the mud and other refuse 85 on the bottom of the cistern to fill said cleaner, when the same may be drawn up at will.

For the purpose of readily removing the refuse contained in the cleaner, we preferably 90 hinge or removably secure said bottom A' or any other suitable portion of said receptacle, so that the same may be readily opened and the refuse easily discharged from the cleaner.

In Fig. 2 we have shown a modified form of the upper valve, in which construction the collar D^3 has no vertical movement in its encircling hub and closely fits the space G^3 , interposed between the flange G' and the top a' , but is provided with an aperture or apertures leading from the bottom g of said collar D^3 upward, and adapted to be registered with a like opening or openings provided in the collar D^3 when the standard D is twisted or rotated in said collar, which is easily allowed, as the collar D^3 is preferably round, and the collar D' may be easily turned upon its supporting-hub E .

The operation of our improved cleaner will be readily understood from the foregoing, and it will be seen that without departing from the spirit of our invention considerable change may be made in the detail, construction, and arrangement of the parts—as, for instance, the relative arrangement and construction of the top valve may be varied, providing that the same is normally closed while the cleaner is being forced into the cistern, and may be opened when the same is in the desired position, and any particular form of bottom valve may be used when desired, and the means for discharging the refuse from the cleaner A may be of any desirable form and construction allowing the refuse to be easily discharged therefrom.

By reference to Figs. 1 and 2 it will be seen that the construction embodied separately in said figures might be combined in a further modification of our cleaner. In Fig. 1 the handle has an up-and-down movement, and when in its upward position connects the aperture b in the collar G to the aperture a in the top of the cleaner-receptacle. In Fig. 2 these apertures are connected together by twisting the handle, which in this figure is shown as having no up-and-down movement; but it will be readily understood that if so desired the aperture b in Fig. 1 might be placed in the collar G sufficiently high, so that when the handle was in its upward position the said aperture would still be closed until the handle having an opening therein, as shown in Fig. 2, was twisted around, connecting the said aperture b and aperture a , as shown in Fig. 2.

It will be observed that in our construction of the top valve we rely upon the same being closed by the buoyancy of the receptacle when the same is being forced into the water, which buoyancy is sufficient to force the top of the receptacle firmly against the collar D^3 , securely closing the aperture a provided therein.

This device may also be used to great advantage in cleaning wells or other receptacles or tanks upon the bottom of which sediment

or refuse matter collects which it is desirable to remove without first removing the water or liquid contained in said receptacle or tank. 65

Having thus fully described our invention, what we claim as new, and desire to secure by Letters Patent, is—

1. The combination, in a cistern-cleaner having a lower valve for the admission of refuse and an upper valve, of a movably mounted handle connected to operate the upper valve when the handle is turned, substantially as and for the purpose set forth. 70

2. In a cistern-cleaner, the combination of the receptacle having a valve in its base, with an aperture or valve in the upper part of the receptacle, a flange-collar above said aperture, and a handle movably mounted in the collar adjacent to said valve and actuated to 80 operate the same, substantially as described.

3. In a cistern-cleaner, the combination of the receptacle A , having a valve in its base, with an aperture or opening a in the upper part of the receptacle, a collar above said aperture and provided with openings b , and the handle movably mounted in the collar adjacent to said aperture and actuated to connect a passage from the opening a in the upper part of the receptacle and the opening b in 85 the collar, substantially as and for the purpose set forth. 9c

4. In a cistern-cleaner, the combination of the receptacle A , having a valve in its base and an aperture or opening a in the upper 95 part of the receptacle, a collar G , mounted above said aperture and provided with openings b , and a flange G' , provided on the collar G , with the handle D , movably mounted in the collar G , the annular shoulder D^3 , interposed between the flange G' and the cleaner-receptacle for closing and opening the aperture a , substantially as and for the purpose set forth. 100

5. In a cistern-cleaner, the combination of a receptacle having a valve in its base, and an aperture or valve in its upper part, with the collar G , mounted above said aperture, a handle D , movably mounted in the collar G , adjacent to said aperture, for opening and 110 closing the same, and a collar E , above the cleaner-receptacle and braced thereto for supporting the movable handle D , substantially as and for the purpose specified. 105

In testimony whereof we have hereunto signed our names, in the presence of two attesting witnesses, at Syracuse, in the county of Onondaga, in the State of New York, this 24th day of November, 1888.

JOHN H. DUNCAN.
FRANK A. HALE.
